UNITED STATES PATENT OFFICE.

JAMES H. BOYE, OF CHICAGO, ILLINOIS.

DESIGN FOR A TIE BACK FOR SIDE DRAPES.

Application filed March 5, 1928. Serial No. 25,671. Term of patent 7 years.

To all whom it may concern:

Be it known that I, JAMES H. BOYE, a citizen of the United States, residing at Chicago, in the county of Cook and State of Illinois, have invented a new, original, and ornamental Design for Tie Backs for Side Drapes, of which the following is a specification, reference being had to the accompanying drawing, forming part thereof.

In the drawings—

Fig. 1 is a front elevation of a tie-back for side drapes, showing my new design;

Fig. 2 is an edge elevation of the same.

I claim:

The ornamental design for a tie-back for side drapes, as shown.

JAMES H. BOYE.
